(57) CLAIM

The ornamental design for a salt lamp with wood enclosure, as shown and described.

DESCRIPTION

FIG. 1 is a perspective view of a salt lamp with wood enclosure showing my new design;

FIG. 2 is a front view thereof;

FIG. 3 is a rear view thereof;

FIG. 4 is a left end view thereof;

FIG. 5 is a right end view thereof;

FIG. 6 is a top view thereof;

FIG. 7 is a bottom view thereof;

FIG. 8 is a rear perspective view thereof;

FIG. 9 is a perspective view of another embodiment of a salt lamp with wood enclosure showing my new design;

FIG. 10 is a front view thereof;

FIG. 11 is a rear view thereof;

FIG. 12 is a left end view thereof;

FIG. 13 is a right end view thereof;

FIG. 14 is a top view thereof;

FIG. 15 is a bottom view thereof; and,

FIG. 16 is a rear perspective view thereof.

The broken lines in the drawings represent unclaimed portions and form no part of the claim.
